UNITED STATES PATENT OFFICE.

ALBERT F. CLEMENTS, OF OSHKOSH, WISCONSIN, ASSIGNOR TO WAITE CARPET COMPANY, OF OSHKOSH, WISCONSIN, A CORPORATION OF WISCONSIN.

SHUTTLE TENSION.

Application filed January 10, 1927. Serial No. 180,184.

The tension device of the present invention is designed to fit into a shuttle for the purpose of regulating the tension applied to the outflowing strand of twine or yarn, and the object of the invention is to so construct the device that a smooth and even spring pressure will be applied to one side of the strand in such a way as to hold the strand firmly against the surface of the feed roller over which it travels, thereby permitting the strand to discharge without impediment and at the same time preventing the possibility of entanglement due to an overfeeding of the strand from the coil carried by the shuttle. The invention also relates to means provided for regulating the spring tension to the desired degree.

Further objects and details will appear from the description of the invention in conjunction with the accompanying drawing wherein:

Figure 1 is a top view of the shuttle showing the tension device of the present invention;

Fig. 2 is a top or plan view of the tension device on enlarged scale;

Fig. 3 is a sectional view taken on the stepped line 3—3 of Fig. 2; and

Fig. 4 is a sectional plan view taken on line 4—4 of Fig. 3.

The device is used in conjunction with the shuttle comprising a body 10 of square dimensions in cross section and tapered at its ends 11 and 12 in the usual manner. The shuttle is tapered on its interior to provide a housing for an elongated coil 13 of yarn, twine, or the like; the interior wall of the shuttle being provided with circumferentially extending teeth or serrations 14 which bear against the surface of the coil and serve to hold its convolutions in properly arranged relation to one another.

The coil is further held in place by the provision of a strap 15 which extends from end to end of the shuttle and is secured at its forward end by the provision of a ring 16 which engages a hook 17 in the body of the shuttle. The above features are common or standard in shuttles now in use and form no part of the present invention.

The shuttle tension device which constitutes the subject matter of the present invention comprises a square base plate 18 which is secured by screws 19 or the like to the floor of the recess in the body of the

shuttle near the discharge orifice 20 through which the twine or yarn passes in leaving the shuttle. The base plate is provided on its inner side with a half conical boss or protuberance 21 which is cored on its interior to afford a conical passage 22 terminating in a reduced aperture 23. The inner wall of the boss or protuberance 21 is beveled at the point 24 where the aperture 23 cuts through said wall so that the conical passage 22 is obliquely truncated, as indicated in Fig. 4. The longer side wall of the aperture 23 terminates at a point in proximate relation to the periphery of a roller 25 which is mounted upon a bearing stud 26 recessed at its upper end to receive a threaded oil cup 27 having a spring-pressed ball 28 enclosing the inlet orifice 29 and having an oil port 30 at the base of the cup for discharging oil to lubricate the roller bearings.

The roller co-operates with an obliquely disposed slightly bowed plate spring 31 which bears against the periphery of the roller and terminates in a re-curved tip 32 extending beyond the roller. The opposite end of the spring is provided with a coil or convolution 33 which is carried around an adjusting post 34 which upstands from the base plate near the inner corner at a point diagonally opposite from the corner over which the twine or yarn passes in discharging. The inturned end 35 of the terminal convolution in the spring is entered into a slot 36 in the side of the adjusting post 34, so that by rotating the post a greater or less amount of tension may be applied to the roller 25.

In order to regulate the spring tension, the upper end 37 of the post is square or flattened to receive the slotted inner end of a T-shaped handle 38 provided at its free end with a cross head having formed therein a series of apertures 40, any one of which is adapted to receive a screw 41 the lower end of which is entered into a lug 42 formed on the side of the boss or protuberance 21 in proximate lateral relation to the discharge orifice 23. By turning the T-shaped handle to the desired degree, and entering the screw 40 through a selected orifice, the spring tension may be regulated.

In use, the twine or yarn is threaded through the conical or funnel-shaped channel 22 and between the roller and spring, so that in passing out over the roller the twine

or yarn will be subjected to the compressive action of the spring which will not interfere with its smooth, easy and regular feeding and will at the same time impose sufficient tension to prevent an overfeeding of the twine or yarn.

The device is simple and compact in structure and easily fits into a shuttle of standard formation, and subserves the purpose intended in a highly efficient manner.

I claim:

1. In a shuttle tension, a member provided with an open-ended guide channel for the passage of twine, a roller in proximate relation to the outfeeding end of said channel, a plate spring positioned to apply tension against said roller, means for regulating the tension of said spring, said means including a rotatable member to which one end of the spring is attached, and means for rotating said member adapted to be secured in several positions of adjustment, substantially as described.

2. In a shuttle tension, a member provided with an open-ended guide channel for the passage of twine, a roller in proximate relation to the outfeeding end of said channel, a plate spring positioned to apply tension against said roller, means for regulating the tension of said spring, said means including a rotatable member to which one end of the spring is attached, and means for rotating said member, substantially as described.

3. In a shuttle tension, a member provided with an open-ended guide channel for the passage of twine, a roller in proximate relation to the outfeeding end of said channel, a spring positioned to apply tension against said roller, and a lever secured to the end of said rotating member and provided with means for holding said lever in different positions of adjustment, substantially as described.

4. In a shuttle tension, a member provided with an open-ended guide channel for the passage of twine, a roller in proximate relation to the outfeeding end of said channel, a plate spring positioned to apply tension against said roller, and a lever secured to

the end of said rotating member and provided with means for holding said lever in different positions of adjustment, substantially as described.

5. In a tension device for shuttles, the combination of a plate provided with a thickened portion cored to afford a tapering open-ended channel, a roller in proximate relation to the reduced end of the said tapered channel, and a plate spring extending in substantially tangential relation to the surface of said roller and positioned to press against the yarn or twine feeding over said roller, substantially as described.

6. In a tension device for shuttles, the combination of a plate provided with a thickened portion cored to afford a tapering open-ended channel, a roller in proximate relation to the reduced end of the said tapered channel, a plate spring extending in substantially tangential relation to the surface of said roller and positioned to press against the yarn or twine feeding over said roller, a rotatably mounted post to which one end of said plate spring is attached, and means for rotating said post and holding the same in adjusted position, substantially as described.

7. In a tension device for shuttles, the combination of a plate provided with a thickened portion cored to afford a tapering open-ended channel, a roller in proximate relation to the reduced end of the said tapered channel a plate spring extending in substantially tangential relation to the surface of said roller and positioned to press against the yarn or twine feeding over said roller, a rotatably mounted post to which one end of said plate spring is attached, means for rotating said post and holding the same in adjusted position, said means being in the form of a lever fitted to the free end of said post and provided with a plurality of apertures, and locking means adapted to engage with a selected aperture for holding the lever in adjusted position, substantially as described.

ALBERT F. CLEMENTS.
